J. STRAKA

SAFETY RAZOR

Filed Dec. 18, 1922

Patented Feb. 9, 1926.

1,572,572

UNITED STATES PATENT OFFICE.

JOHN STRAKA, OF CHICAGO, ILLINOIS.

SAFETY RAZOR.

Application filed December 18, 1922. Serial No. 607,652.

To all whom it may concern:

Be it known that I, JOHN STRAKA, a citizen of the Republic of Czechoslovakia (who has declared his intention of becoming a citizen of the United States), and a resident of Chicago, in the county of Cook and State of Illinois, have invented a new and useful Improvement in Safety Razors, of which the following is a full, clear, and exact description.

My invention relates to improvements in safety razors, and it consists in the combinations, constructions, and arrangements herein described and claimed.

15 An object of my invention is to provide a safety razor in which the head may be instantly removed from the handle portion in a single operation, thus freeing the blade from the razor without the necessity of unscrewing the handle from the head which is customary in the ordinary type of razor.

20 A further object of my invention is to provide a device of the character described in which the blade may be flexed so as to dispose the cutting edges thereof at the desired angle.

25 A further object of my invention is to provide a device of the character described in which a reservoir is provided beneath the blade so as to retain the waste matter, thereby obviating the clogging of the waste matter about the comb and cutting edge of the razor.

30 A further object of my invention is to provide a device of the character described in which there are only three separable parts when disassembling the razor for cleaning, these parts being the head portion, the blade, and the handle portion.

35 A further object of my invention is to provide a device of the character described which has novel means for releasing the comb portion from the handle when it is desired to pack the razor into a small space.

40 A further object of my invention is to provide a device of the character described which has positive means for locking the head portion to the handle.

45 A further object of my invention is to provide a device of the character described which is relatively simple in construction, and which is durable and efficient for the purpose intended.

50 Other objects and advantages will appear in the following specification, and the novel

features of the invention will be particularly pointed out in the appended claims.

My invention is illustrated in the accompanying drawings, forming part of this application, in which—

55 Figure 1 is a vertical section through the device,

Figure 2 is a vertical section at right angles to the section shown in Figure 1, which shows the head as being removed from the handle portion,

60 Figure 3 is a plan view of the comb portion,

Figure 4 is a section along the line 4—4 of Figure 1,

65 Figure 5 is a section along the line 5—5 of Figure 1,

Figure 6 is a vertical section of a modified form of the device, and

70 Figure 7 is a vertical section of another modified form of the device.

75 In carrying out my invention, I provide a handle portion 1 which has a bore 2 therein that is reduced at 3 so as to provide a seat for a push button 4. The handle 1 is connected to a comb 5 by means of a tubular member 6. As clearly shown in Figure 1, the member 6 is rigidly secured to the handle 1 and has its upper end fashioned into spring catch members 7 that are adapted to enter an annular groove 8 in the bottom of the comb portion 5. The free ends of the catch members 7 are provided with shoulders 9 which engage with the inwardly extending flange 10 of the comb 5.

80 In Figures 1 and 2, I have shown a novel means for moving the catch members 7 inwardly so as to release the member 6 from the member 5. This means comprises a sleeve 11 which is slidably disposed upon the member 6, and which is adapted to move the catch members 7 inwardly so as to release the member 6 from the comb 5 when the sleeve 11 is moved so as to cover the catch members 7. When the sleeve 11 is disposed at the end of the member 6, the member 5 may be readily removed from the member 6, whereby the razor can be packed in a small space.

85 100 105 110 The member 5 is adapted to carry a blade 12. The blade 12 is flexed by a head portion 13, whereby the person using the device may flex the blade so as to dispose the cutting edges of the blade in the desired angle. As clearly shown in Figure 3, the

comb portion 5 has upwardly extending lugs 14 on its upper surface, these lugs being adapted to support the blade 12. The blade is flexed by means of moving the head portion 13 downwardly toward the member 5. The blade may be flexed to any desired angle so as to be disposed at the proper angle when the device is used for shaving.

It will be noted that the blade is spaced 10 above the upper surface of the comb 5 by means of the lugs 14, whereby space is provided between the blade and the comb for receiving waste matter. In this manner the cutting edge of the blade is kept clean.

15 As heretofore stated, when the sleeve 11 is moved toward the free end of the member 6, it causes the catch members 7 to move toward each other so as to release the comb 5 from the member 6. When the head 13 20 is disposed upon the comb 5, the threaded shank 15 of the head enters the free end of the member 6. It will be noted that this end of the member 6 is internally threaded, the threads on the member 6 being adapted 25 to engage with the threads on the shank 15 so as to hold the head 13 in place. When the head 13 is disposed in place, a movement of the sleeve 11 toward the comb 5 will cause the catch members 7 to free the 30 member 5, but before this is done, the catch members 7 will engage with the shank 15 to hold the latter in place.

In this manner, the head 13 is secured 35 to the member 6 before the member 5 is released by the catch members 7. The head 13 holds the comb 5 in place. In releasing the head 13 from the member 6, the movement of the sleeve 11 away from the comb 5, causes the catch members 7 to be operatively 40 connected to the member 5 before the head 13 is released. In this manner, the member 5 is carried as a unit with the member 6 when the head 13 is released from the member 6.

45 The handle 1 carries a novel locking mechanism which is adapted to prevent any movement of the sleeve 11 after it is once moved toward the free end of the member 6. The sleeve 11 can only be moved 50 when the push button 4 is pressed. The mechanism which operatively connects the push button 4 with the sleeve 11 is clearly disclosed in Figures 1 and 2. A fork-shaped member 16 is disposed within the member 6 and is rigidly secured to the portion 1 of the handle by means of a pin 17. Locking prongs 18 of the member 16 are slidably disposed in the slots 19 of the member 6 and are adapted to move outwardly so as 55 to be disposed in an annular groove 20 of the sleeve 11. The prongs 18 are adapted to engage with a shoulder of the groove 20 so as to prevent movement of the sleeve 60 11 away from the member 5.

65 Means for moving the prongs 18 inwardly

so as to release the sleeve 11 is mounted in the handle portion 1, and consists of a U-shaped member 21 which has its sides rounded slightly so as to conform to the curvature of the inner surface of the member 6. The member 21 abuts the push button 4 and terminates adjacent to the prongs 18. The prongs 18 have cam edges 70 22 upon which the member 21 rides when actuated by the push button 4 so as to swing 75 the prongs 18 toward each other, thereby releasing the sleeve 11.

A spring 23 bears against the lower end of the member 6 and rests upon outwardly extending lugs 24 of the member 21. The spring 80 yieldingly holds the member 21 against the push button 4, thus causing the push button to be held in extended position.

From this construction it will be apparent 85 that when the push button 4 is moved inwardly, it will move the member 21 so as to cause the inner end of the member to slidably engage with the cam edges 22 of the prongs 18, whereby the prongs 18 90 are swung inwardly so as to release the sleeve 11. The sleeve 11 may now be moved away from the member 5.

From the foregoing description of the 95 various parts of the device, the operation thereof may be readily understood. The device is constructed so that there will be a minimum number of parts when it is taken apart for cleaning. It will be noted 100 that only the head 13, the blade 12, and the handle are the parts which are separated from each other when the device is cleaned. As heretofore stated, the handle carries the member 5 when the head 13 is removed. The device may be quickly assembled with 105 only one turning of the handle being required. In the ordinary safety razors, the handle is turned through a great number of revolutions so as to cause the head to flex the blade 12 to a sufficient angle. With 110 my present form of the device, it is merely necessary to place the blade upon the member 5 and dispose the head 13 in position so that the shank 15 thereof enters the member 6.

115 The member 6 is now moved downwardly, without turning, to the desired position, and is then clamped in place by means of the sleeve 11. The moving of the sleeve 11 toward the member 5 causes the catch member 7 to engage with the shank 15, thereby holding the head 13 in place. A rotation of the handle 1 through one revolution is sufficient to flex the blade 12 to the desired angle.

120 When the device is to be packed away, the head 13, the blade 12, and the member 5 are 125 disengaged from the handle 1. When removing the head 13 from the handle 1, the push button 4 is actuated so as to move the prongs 18 inwardly in the manner hereto-

fore described and to release the sleeve 11. The sleeve 11 is now manually moved away from the member 5, whereupon the catch members 7 will engage with the member 5 and will release the head 13. After the head 13 is removed from the device, the member 5 may also be removed by again moving the sleeve 11 toward the free end of the member 6. This movement releases the 10 catch members 7 from the member 5.

It will be observed that the sleeve 11 is positively locked against accidental movement in this form of the device.

In Figure 6 I have shown a modified form 15 of the device. This form is identical with the form heretofore described, except that the locking mechanism for positively holding the sleeve 11 in closed position is not used. This form of the device does away 20 with the member 16, the member 21, the spring 23, and the push button 4. The other parts of the device are identical with the parts heretofore described in the preferred 25 form of the invention, and will therefore need no further description. Like parts in 30 both forms of the device will have like reference numbers. The handle portion 1 in this form of the device has its lower end closed, since it does not receive the push button 4.

The operation of this form of the device is practically identical to the operation of the preferred form. In this form of the device, the sleeve 11 is frictionally held in 35 place and is not locked in place by the prongs 18. In this form of the device, as in the preceding form, the member 5 is carried by the handle 1, even though the head 13 is removed. To release the member 5, the sleeve 11 has to first be moved 40 away from the member 5, and then to be moved toward the member 5 after the head 13 is freed.

The device provides a simple mechanism 45 whereby the blade 12 may be readily secured in place with only one rotation of the handle instead of a number of rotations as is usually required with the ordinary razor. Furthermore, the device is simple in construction, compact, and is not likely to easily 50 get out of order. The catch members 7 provide a novel means for holding the member 5 in place when the head 13 is removed and for also holding the head 13 on the device. The spacing of the blade 12 from the member 5 55 provides a reservoir between the blade 12 and the member 5 which is adapted to receive the waste matter. The cutting edges of the blade 12 are therefore kept clear of waste matter while the device is being used 60 for shaving.

In Figure 7 I have shown another modified form of the device. In this form of the device, the sleeve 11 is extended so as to take 65 the place of the handle 1, in Figure 1, of

the device. In this modified form of the device, the handle 30 extends from the comb portion to the cap 31. The cap 31 is secured to the handle 30 by any means, such as by screwing or force fitting. A tubular 70 member 32 takes the place of the member 6 and is rigidly secured to a push button 33 at 34. The button 33 extends through an opening 35 in the cap 31 and is provided with a head 36 which determines the inward 75 movement of the button. The cap 31 has a key 37 which slides in a slot 38 in the push button 33, thereby preventing a rotation of the push button 33 with respect to the cap 31.

From this construction it will be observed that when the push button 33 is moved inwardly, the tubular member 32 is moved outwardly from the opposite end of the handle 30 and the catch members 39 of the member 32 swing outwardly. This movement releases the catch member 39 from the shank 15 of the head 13. When it is desired to again secure the handle 30 to the comb portion 5 and the head 13, it is merely 90 necessary to insert the shank 15 of the head 13 in the threaded bore of the member 32. The handle 30 is now grasped and is moved toward the comb 5. This movement continues until the end of the member 32 engages with the comb 5, whereupon further movement of the handle 30 will cause the handle to move over the catch members 39 and cause them to swing inwardly to grip the shank 15. The handle 30 may now be rotated and will rotate the member 32 so as to tighten the handle onto the comb 5. As heretofore stated, only one revolution of the handle 30 is necessary to effect the tightening 95 of the handle to the member 5 and the head 13.

I claim:

1. A safety razor comprising a handle, a blade carrying member, means carried by said handle for removably securing said member to said handle, and a head member for clamping a blade to said blade carrying member, said means being adapted to lock said head to said handle, said means releasing said blade carrying member after it engages with said head, whereby said head holds said blade carrying member in position.

2. A safety razor comprising a handle, a tubular member having one end rigidly secured to said handle and having its other end internally threaded and slotted, a head having a threaded shank adapted to enter the slotted end of said tubular member, and manually operated means for causing the portions of the slotted end of said tubular member to grip said shank.

3. In a safety razor, a handle, a comb portion having an annular groove, a tubular member carried by said handle and having a slotted end, the strips at the slotted end hav-

ing outwardly extending shoulders adapted to be received in said groove to hold said comb to said handle.

4. In a safety razor, a handle, a comb portion having an annular groove, a tubular member carried by said handle and having a slotted end, the strips at the slotted end having outwardly extending shoulders adapted to be received in said groove to hold 10 said comb to said handle, and manually operated means for moving said strips inwardly to release said strips from said comb.

5. A safety razor comprising a handle, a 15 tubular member carried by said handle and having a slotted end, a comb portion having an annular groove therein, the slotted end of said tubular member defining strips, said strips having shoulders adapted to be received in said annular groove to hold said comb to said handle, a head portion having a shank adapted to enter the slotted end of said tubular member, said tubular member being internally threaded, and said shank 25 being exteriorly threaded, and means for moving said strips inwardly to grip said shank, the shoulders of said strips being removed from said annular groove when said strips engage with said shank.

30 6. A safety razor comprising a handle, a tubular member carried by said handle and

having a slotted end, a comb portion having an annular groove therein, the slotted end of said tubular member defining strips, 35 said strips having shoulders adapted to be received in said annular groove to hold said comb to said handle, a head portion having a shank adapted to enter the slotted end of said tubular member, said tubular member being internally threaded, and said shank 40 being exteriorly threaded, means for moving said strips inwardly to grip said shank, and means for locking said first named means against movement.

7. A safety razor comprising a handle 45 having one end threaded and slotted, a razor blade retaining head having a threaded shank adapted to enter the slotted end of said handle, and means for causing the portions of the slotted end to grip said shank 50 whereby said handle may be screwed on the shank in the ordinary manner.

8. A safety razor comprising a blade flexing head having a threaded shank, a handle, a threaded sleeve carried by said handle for 55 loosely receiving said shank, and means for collapsing said sleeve so as to operatively engage with said shank, whereby a rotation of said sleeve will cause said shank to move said blade flexing head.

JOHN STRAKA.
